UNITED STATES PATENT OFFICE.

ESLEY C. DE BOLT, OF SEATTLE, WASHINGTON.

CARTRIDGE-BELT.

1,234,298.

Specification of Letters Patent. Patented July 24, 1917.

Application filed February 17, 1916. Serial No. 78,849.

To all whom it may concern:

Be it known that I, ESLEY C. DE BOLT, a citizen of the United States, and a resident of Seattle, in the county of King and State of Washington, have invented certain new and useful Improvements in Cartridge-Belts, of which the following is a full, true, and exact specification.

My invention relates to improvements in cartridge belts and has for its principal object to provide an improved and novel belt construction which frictionally retains all of the cartridges in the belt with an equal retaining friction on all cartridges; to provide a belt of the above type in which the frictional grip of the belt on the cartridge is adjustable and which depends upon the tightness of the belt about the body of the wearer; to provide a cheap belt of manufacture in which small scrap leather is utilized. A further object is to provide improved take up and removing fastenings for the belt. In the usual friction cartridge pocket belts, there is no provision for maintaining a constant and uniform friction on all cartridges with the result that many pockets become too loose and drop the cartridges while others are too tight. The usual type of cartridge belt is difficult to properly repair. My belt overcomes the above objections.

Other objects will appear as my invention is more fully explained in the following specification, illustrated in the accompanying drawings and pointed out in the appended claims.

In the drawings, Figure 1 is a fragmentary plan of my belt. Fig. 2 is an enlarged detail elevation of same. Fig. 3 is a plan of Fig. 2.

Referring more particularly to the drawings, Figs. 1, 2 and 3, numerals 1 and 2 indicate end straps of a belt. End strap 1 is secured to a hook 3 which is caught on a buckle ring 4 from which it is unhooked when the belt is removed from the wearer. Strap 2 passes slidably through ring 4, doubles back upon itself and has an eyelet hook 5 on its extreme end which adjustably engages holes 6 in the said strap. An adjusting buckle may be placed in strap 1 if desired to make major adjustments. The opposite ends of straps 1 and 2 are connected by a series of similar links 7 each of

which is formed from a piece of material 55 and consists of a solid back strip 8 having parallel transverse holes 9 punched in it, and a pair of similar front strips 10 which are integral with said back strip and each of which is punched with a hole 10 which 60 registers with one of the holes in the back strip when the front strips are folded back upon the back strap as shown. Both front and back strips are chamfered as at 11. A chain is formed of the twin links just described by passing the front strips of one link through the holes 10 of both front and back strips of the preceding link. Thus a continuous chain is formed of links of 65 soft material such as leather and of such 70 length as to leave room to insert a cartridge 12 between the front and back strips of each link. The tightening of the belt about the wearer frictionally retains the cartridge. The said friction may be adjusted by the tightening or loosening of the belt. When a number of cartridges have been withdrawn, the belt is retightened by means of hook 5 and holes 6. It will be understood that all cartridges are held with 75 equal frictional resistance.

While I have shown a particular form of embodiment of my invention, I am aware that many minor changes therein will readily suggest themselves to others skilled in 85 the art without departing from the spirit and scope of the invention, and I therefore desire to avoid being limited to the exact form shown and described. Having described my invention, what I claim as new 90 and desire to protect by Letters Patent, is—

1. In a cartridge belt, the combination of a plurality of interconnected cartridge retaining links arranged continuously, and adjusting means, whereby the retaining friction of all the links is adjustably controlled, 95 said adjustable controlling means including a hook on one end of said belt.

2. A cartridge belt, formed of a plurality of flexible twin links arranged in the form 100 of a continuous chain and adapted to each frictionally retain a cartridge, and adjustable take-up means connecting the two ends of said chain, whereby the cartridge retaining friction of each link is variable simultaneously.

ESLEY C. DE BOLT.
